[57] **CLAIM**

The ornamental design for a Christmas tree stand, as shown and described.

DESCRIPTION

FIG. 1 is a front side, right side and top perspective view of a Christmas tree stand, showing my new design;
FIG. 2 is a top plan view thereof;
FIG. 3 is a bottom view thereof;
FIG. 4 is a front side elevation view thereof, with the rear side elevation view being a mirror image; and,
FIG. 5 is a right side elevation view thereof, with the left side elevation view being a mirror image.
